UNITED STATES PATENT OFFICE.

GEORGE C. BEIDLER, OF ROCHESTER, NEW YORK.

PHOTOGRAPHIC AND DEVELOPING APPARATUS.

1,187,241.

Specification of Letters Patent. Patented June 13, 1916.

Application filed September 28, 1909, Serial No. 519,932. Renewed November 12, 1915. Serial No. 61,168.

To all whom it may concern:

Be it known that I, GEORGE C. BEIDLER, a citizen of the United States of America, and resident of Rochester, in the county of 5 Monroe and State of New York, have invented certain new and useful Improvements in Photographic and Developing Apparatus, of which the following is a specification.

10 This invention relates to photographic, printing and developing apparatus having the combined functions of exposing the film to the action of light and of thereafter treating the same, the said apparatus being 15 here shown as motor-driven and having means actuated by the mechanism for controlling the motor.

An object of this invention is to produce 20 a photographic and developing apparatus in operative relation to each other, the said developing apparatus having a receptacle for fluid, which fluid will act on the coated surface of the film and with relation to which a rotary member, preferably in the 25 form of a drum, is supported and adapted to displace the fluid to such an extent as to make it possible to employ a minimum quantity of fluid for the purpose of immersing the film, means being also provided for delivering film to the receptacle and for removing it therefrom.

It is furthermore an object of this invention to provide a receptacle in operative relation to the means for removing the film 35 from the first mentioned receptacle, the second mentioned receptacle being adapted to contain liquid preferably of the character of fixing fluid. In order to cause the film to enter the second mentioned receptacle 40 and to lie flat therein after it has been released by the means for removing the belt from the first mentioned receptacle, I supply the second mentioned receptacle with a spraying attachment designed to force 45 liquid and I utilize the force of such liquid to cause the film to travel in the second mentioned receptacle while, at the same time, acting on said film to cause it to lie flat in the liquid contained in the second 50 mentioned receptacle, and furthermore an object of the invention is to provide mechanism for spreading the film and mechanism for immersing the film.

A still further object of this invention is 55 to provide a motor for driving the appara-

tus and means actuated by a part of the apparatus for controlling the motor.

Furthermore, an object of this invention is to provide a conveyer or carrying device preferably comprising an apron or belt with 60 which a flexible device such as a chain or the like coats to retain the film on an apron or belt while the said film is being subjected to the action of developing or other fluid.

With the foregoing and other objects in 65 view, the invention consists in the details of construction and in the arrangement and combination of parts to be hereinafter more fully set forth and claimed.

In describing the invention in detail, reference will be had to the accompanying drawings forming part of this specification, wherein like characters denote corresponding parts in the several views, in which—

Figure 1 illustrates a view in side elevation of a photographic and developing apparatus embodying the invention; Fig. 2 illustrates a view in elevation of a part of the interior mechanism; Fig. 3 illustrates an elevation of the interior mechanism from 80 the opposite side; Fig. 4 illustrates a portion of the apparatus partly in section; Fig. 5 illustrates a view in elevation showing the end of the apparatus, a part thereof being in section; Fig. 6 illustrates a detail plan 85 of the rear of the apparatus; Fig. 7 illustrates a side elevation of a portion of the rear of the apparatus; Fig. 8 illustrates a detail plan view of the pump and sprinkler; Fig. 9 illustrates a detail view of a power 90 transmitting mechanism; Fig. 10 illustrates a perspective view of a film immersing frame; Fig. 11 illustrates a modification with the spraying attachment applied to a hand operated machine; and Fig. 12 illustrates a detail of the tripping mechanism.

In these drawings A indicates a casing for the developing apparatus covered by a magazine B, adapted to contain a supply of film here illustrated as in the form of a roll B'. 100 The side of the magazine has an exposing chamber A⁵, and a camera D is applied to the side of the magazine for exposing the film in the exposing chamber to light.

The magazine is provided with appropriate brackets such as A² appearing in Fig. 1 for supporting the roll B', the film from which is run over the idler A⁴, into the exposing chamber A⁵, where it is in position to be acted on by light admitted through the 110

camera D. The magazine is preferably above the casing A and acts as a cover for said casing. The front a of the casing is stationary with relation to the base a' , where-
5 as the sides and back are connected to the magazine and the back is hinged to the base, thus allowing the sides and back of the cas-
ing to be swung rearwardly with the maga-
zine for the purpose of permitting access to
10 the interior of the apparatus.

The rear of the casing has an opening a^2 and below the opening brackets a^3 are at-
tached to the casing. A pan or receptacle
15 a^4 is supported by the bracket a^3 and said
pan projects into the casing through the
opening a^2 . The purpose of the receptacle
 a^4 is to contain a fixing fluid into which de-
veloped films are delivered. Under ordinary
20 conditions the light would not be sufficiently
strong to affect a developed print coming
from the developing apparatus (to be here-
inafter described) but for the purpose of
providing a safe-guard against action of
25 light on a developed print, a hood a^5 is re-
movably secured to the casing in any ap-
propriate manner.

The casing contains a tank or receptacle
E adapted to receive developing fluid and
said tank may have ends e , in which the
30 shafts F and G are journaled or said shafts
may be suitably journaled in operative rela-
tion to the receptacle.

The receptacle may be supported by the
35 plates H secured to the base and said re-
ceptacle has a drain pipe I to which the
cock J is connected, said cock extending
through the side of the casing. A drip pan
K is located under the receptacle and is pro-
40 vided with a drain nipple k , extending
through the base. The drip pan is pro-
vided to collect the drippings from the
chains, conveyers and rollers, to be presently
described. Shafts k' extend between the
45 plates H and support the pan K by passing
through apertures in its sides and said shafts
carry pulleys k^2 , over which chains travel.
The shaft F has an extension passing
through the side of the casing on which is
50 mounted a stub shaft 20 (Figs. 5 and 9) and
said stub shaft is provided with a sleeve 21
supplied with a shoulder 22 at one end and
has its opposite ends screw threaded as
shown at 23. The sleeve is further provided
55 with a longitudinally disposed groove 24.
The sleeve is anchored on the stub shaft at
any position desired through the medium
of a set screw 25. A worm wheel 26 has its
hub rotatable on the sleeve and said worm
60 wheel has its side recessed to form a clutch
member as shown at 27, the said worm wheel
being engaged by a worm 28, mounted on
the shaft 29 of the motor 30, the said motor
being here shown as an electrically driven
65 type, although I do not wish to be limited
with respect to the style of motor employed.

The clutch member 31 is slidable on the
sleeve and has a friction face 32 adapted to
act in conjunction with the clutch member
formed on the worm wheel 26. The hub of
the clutch member 31 is provided with screws
70 33, which are threaded therein and have
shanks extending into the grooves 24 in the
sleeve. The function of these screws and
their shanks is to permit the clutch member
31 to move longitudinally of the sleeve but
75 to prevent rotation of the clutch member 31
on the sleeve. In other words, the office of
the clutch member 31 is to communicate mo-
tion of the worm wheel 26 to the sleeve and
as the sleeve in turn is coupled to the stub
80 shaft it follows that the stub shaft will be
rotated and as the stub shaft is connected
to the shaft F, power is communicated to
the mechanism for feeding and conveying
the film. A spring 34 encircles a portion
85 of the sleeve and has one end bearing against
the clutch member 31 whereas the opposite
end of the spring 34 bears against the nut
35 which engages the threads 23 on the
sleeve. By means of this nut, tension of the
spring 34 is controlled.

Ends of the shafts F and G have sprocket
wheels f and g , respectively, and said
sprocket wheels are connected by a sprocket
chain M, by which motion of the shaft F is
90 communicated to the shaft G, and the shaft
G also has a pinion G'' meshing with a gear
wheel G''' for driving the roller z^2 .

A frame N is removably supported above
the receptacle and said frame has a depend-
ing arm n at each end forming supports for
the rotatable drum O. The drum may be
hollow and is preferably comparatively
large with respect to the receptacle in which
it is supported for, by this construction, the
developing fluid contained in the receptacle
is displaced and a small quantity of the
developing fluid will be sufficient to completely
immerse a film as it is carried by the drum.
One end of this drum is provided with a per-
100 pheripheral gear P, meshing with a pinion Q,
rotatable on a stud q projecting from one
of the arms. The pinion Q is driven by a
gear wheel R on a shaft S, the said gear
wheel R taking motion from a gear wheel
110 R', mounted on the shaft G.

The end of the drum opposite the periph-
eral gear P is recessed to form a shoulder T
and said shoulder is engaged by a dog U,
which is slidably mounted on a stud V, the
120 said dog being pulled downwardly by the
spring v . Under ordinary conditions, the
weight of the dog will be sufficient to cause
it to move longitudinally, but in order to
insure positive action, the spring v is pro-
vided. The object of the dog U is to arrest
the drum at each complete rotation of the
said drum and as the shoulder of the drum
contacts the end of the dog, the dog is ele-
125 vated slightly until it has moved a distance
130

equal to the length of the slot v' . The dog U is further utilized to operate the switch 36 which may be of a type to close under the tension of the spring when the dog U disengages said switch. That is to say, when the dog is elevated through its engagement with the drum, the upper end of the said dog engages the switch and opens it, thereby cutting out current to the motor but on the descent of the dog U and its disengagement with the switch, the spring of the switch operates to cause an engagement of the contacts of the switch, thereby completing circuit through the switch to the motor.

15 As shown in the drawings, the conductor conduit 37 extends inside of the case and the conductors 38 and 39 extend therethrough and project from the coupling 40 to the terminals of the switch.

20 41 is a conductor which may be connected to any source of electrical supply and it extends through the insulating box 42 to the conduit 37, the wires from the switch to the motor being extended through the conduit 25 43 and through the box 42. In fact, any appropriate wiring may be employed for connecting a motor to the source of electrical supply through which a switch or cut-out operated by mechanism is employed in 30 connection with the apparatus.

The mechanism is brought to rest at such time as the print is immersed in the developing fluid contained in the tank and the mechanism cannot be operated until the dog 35 U is moved out of engagement with the shoulder T. This is accomplished by the lever W which is journaled in the casing and has an arm W' bearing against a stud W' on the dog. Pressure on the outer end of 40 the lever results in pressure on the upper end of the dog which will cause the lower end of the dog to swing out of engagement with the shoulder. When the lower end of the dog is clear of the shoulder T, it is free 45 to drop so that its end clears the shoulder T of the drum. The switch will be closed to conduct current to the motor for the purpose of starting the motor as heretofore indicated. The periphery of the drum being 50 cut away, as explained, also permits the arm X to be moved with relation to the dog w on the feeding and cutting roller to be hereinafter referred to.

The arm X is held normally depressed by 55 means of the spring x and when the drum rotates sufficiently to bring the recessed portion thereof under the arm X, the said arm is depressed until its upper end clears the end of the dog w. When the dog is released, 60 the spring forces its nose into engagement with the ratchet wheel Y on the shaft y and hence rotation of the shaft is communicated to the feeding roller Z, it being understood that the dog w is pivoted on the feeding 65 roller and that the spring w' holds the nose

of the dog normally in engagement with the ratchet wheel Y.

For the purpose of holding the arm X normally elevated a cam Z' is mounted on the frame N and may be moved to hold the 70 arm normally elevated in which position the said arm will hold the dog out of engagement with the ratchet wheel and the shaft y may be rotated without operating the feeding roller.

When the print is caused to travel between the feeding roller Z and the rollers z, it is punctured at each rotation of the feeding roller by the serrated blade Z² on the feeding roller, and the print is then directed between the two rollers z' and z², and from there to the interior of the developing apparatus where the print is delivered to the conveyor consisting of a chain S' and the belt S².

In operation when the parts are in the position shown in Fig. 4, the cam Z' is moved to disengage the arm X and the lever W, pressed to move the end of the dog U out of engagement with the shoulder T. 90 The dog will then move longitudinally and will pass the shoulder T so that the drum will be free to rotate. Power being applied to the shaft F, the shaft G will be rotated through the medium of the sprocket wheels 95 and chain and the gear wheel R, taking motion from the shaft G, heretofore described, will turn the gear wheel Q and communicate motion to the drum.

When the drum is rotated slightly, the 100 arm X descends into the recess of the drum and the upper end of said arm clears the dog w and permits the spring to force the nose of the dog into engagement with the ratchet wheel. By this means, the motion of the 105 shaft y which normally rotates freely in the drum is communicated to the feeding and cutting roller Z, and the film is drawn between the roller Z and the roller z and punctured, that is to say, a film is punctured with each complete rotation of the roller Z, and 110 said film is directed between the rollers z' and z². After the arm X is elevated to the periphery of the drum, the upper end of the 115 said arm stands in the path of travel of the dog w as it is carried around with the feeding and cutting roller Z, and when the said dog contacts the arm, the nose of the arm is thrown out of engagement with the ratchet wheel Y and the shaft y, is permitted to rotate independently of the feeding and cutting roller. Though the feeding and cutting roller comes to rest, the rollers z' and z², continue to rotate, drawing the film downwardly and causing the film in engagement 120 with the said rollers z' and z², to be severed from the body of the film on the puncture line heretofore referred to. The film thus severed will be delivered to the conveyor 125 consisting of the chain and belt heretofore 130

mentioned. The shaft y , is driven through the medium of the gear wheel y' , meshing with the gear wheel y^2 , on an end of the roller z' . The roller Z' , is positively driven by a gear wheel z^3 , meshing with the peripheral gear z^4 , on the feeding and cutting roller Z , and the rollers z' and z^2 , are preferably positively driven by being geared together at one end.

- 10 The frame N is provided with a roller N' which is relatively small, around which a belt or apron travels and it has been found in practice that a film after having been carried through the developing tank by means 15 of the belt or apron and the chains which hold the film on the belt or apron, said film being saturated, will adhere to the surface of the belt or apron to a sufficient extent to cause the said film to travel with the belt or 20 apron from the point of disengagement of the chain with the film, which is at the shaft F until the said belt or apron starts to encircle the roller N' , but owing to the abruptness of the turn over the roller, the said film 25 will break away from the belt or apron and descend by gravity into the pan or receptacle a^4 which contains the fixing fluid.

The belt may be tightened or adjusted to make it run straight on the shaft F through 30 the medium of an arm 53 which is engaged by the end of a rod 55, which rod is threaded in the lug 56. The end of the tank has a slot F^2 to permit movement of the shaft F . By 35 rotating the rod 55, the arm is raised or lowered and as the shaft F is journaled in the arm, the movement of the shaft affects the belt which runs over the said shaft. The rod 55 extends through the bottom of the casing in order that it may be reached from 40 the outside for the purpose of manipulating the parts to effect the proper adjustment.

In addition to the hand operated means for tripping the dog U , I employ a flexible connection 57 run over a pulley 58 and connected to a bell crank 59 for tripping the mechanism to start the motor. As shown, the bell crank is pivoted on a bracket 60 secured to one of the legs of the casing and the said bell crank has another connection 50 61 which extends up into the casing and is fastened to a long arm 61^a of a bell crank lever, the short arm 62^a of said lever acting on the stud W^2 extending from the dog W . Any appropriate means may be provided for 55 pulling the flexible connection 57.

I extend the motor shaft 29 into the casing 62 of the pump and connect the casing of the pump with the receptacle a^4 for the fixing fluid through the medium of the pipe 63. The pipe 63 acts to conduct the liquid from the receptacle a^4 to the pump casing. The pump is of the ordinary centrifugal type and the liquid which reaches the casing is acted on and is forced through the outlet 65 pipe 64 to the sprayer pipe 65, which sprayer

pipe is provided with a series of apertures discharging approximately horizontally and longitudinally of the receptacle a^4 to which it is applied. The ends of the sprayer pipe are provided with caps 66 which may be removed for the purpose of cleaning the said sprayer pipe.

The holes in the sprayer pipe discharge at about the level of the liquid contained in the receptacle so that the current occasioned by the liquid catches the film as it is descending into the receptacle and acts on said film to propel or carry it rearwardly in the receptacle and, at the same time, a current of liquid acts on the coated surface of the film and on the top of said film, the said action tending to submerge the film in the receptacle. It has been found in practice that as the film descends into the receptacle, the liquid emitted from the sprayer pipe straightens it and causes it to float rearwardly of the receptacle, as stated.

In Fig. 11, I show a hand operated device in which the belt 67 or other flexible connection is driven by the rotary member 68 which rotary member is mounted on the shaft 69 corresponding with the shaft F heretofore described. The pump 70 has a pulley 71 from which the flexible connection is run and the pump is in communication with the receptacle a^4 by means of the pipe 72, which pipe acts as a feeding pipe for the pump, whereas the discharge pipe 73 of said pump conducts the liquid to the sprayer pipe 74 which is of the same construction as the sprayer pipe 65 heretofore described.

While I have stated that the spraying apparatus was designed to spread the film after it has been delivered into the receptacle a^4 , I have found it desirable to provide mechanically operated means for spreading the film which mechanically operated means may be used independently or in conjunction with the spraying apparatus. I have attained very satisfactory results by using them in conjunction with each other and in the relation shown in Figs. 2, 3, 4 and 6 of the drawings.

The mechanically operated spreading means heretofore described is shown in the drawing in the form of lengths of material which are bent to form the spreading members proper, each of which lengths of material is preferably bent whereby the arm 75 is formed and in which an intermediate straight portion 76 is journaled in a bracket 77, which bracket 77 is attached to the casing; the end of the length of material being formed into a crank 78 above the said bracket. As shown in the drawings one bracket and spreading member is attached at each side of the opening in the casing. A spring 79 encircles the portion 76 and has one end bearing against the arm 75 and exerting pressure thereon, to swing the mem-

ber in the bracket in order that the arm may travel from the position shown in full lines in Fig. 6 to the position shown in dotted lines in said Fig. 6, as will be seen by an inspection thereof. The arms swing outwardly in opposite directions when power is applied to the cranked end of the member and in order to swing the said arms oppositely, it is necessary that the crank of one member be at an angle with relation to its arm different from the angle of the crank of the other member with relation to the arm of the last mentioned member. The relation of the parts just mentioned is shown in Fig. 15 6 and the cranks of the members are connected by a thrust rod 80 which thrust rod has a link 81 pivoted to it intermediate its length by which motion is communicated to the said thrust rod. The outer end of the 20 link 81 is pivoted to a collar 82, and the collar in turn is connected to an oscillating lever 83 which is journaled in a bracket 84 attached to the casing. The end of the oscillating lever remote from the collar is 25 moved in one direction by a cam 84^a projecting from the side of the spur wheel 85 which spur wheel is mounted on a stud 86 anchored to the casing in any appropriate way. The spur wheel 85 is driven through 30 the medium of a pinion 87 which is mounted on the stub shaft 20, and therefore as the developing apparatus is operated, motion is communicated to the mechanism for spreading the film. An inspection of Figs. 6 and 7 35 will show that the lever is moved by the cam 84^a against the action of the springs 79 until the end of the cam is reached and at which position the arms 75 will have traveled outwardly as shown in full lines, Fig. 6, 40 the said arms being returned immediately thereafter to the dotted line position of Fig. 6 under the influence of the springs when the said lever has been released by the cam. The members are in such relation to the developing apparatus that the arms operate to 45 spread each film as it is delivered to the receptacle *a¹*. This same apparatus may be employed in connection with the hand operated machine shown in Fig. 11, by providing 50 the shaft 69 with a pinion similar to the pinion 87 and duplicating the parts of the spreading apparatus heretofore described. The throw of the lever 83 may be regulated by moving the collar 82 thereon nearer to or 55 farther from the pivotal point, the said collar being provided with a set screw 88, to effect the desired adjustment.

In addition to the mechanism for spreading the film, I provide means for submerging the film which submerging means acts in conjunction with the other apparatus for developing and spreading it. The embodiment of the submerging apparatus here shown consists of a frame 89 which is approximately rectangular in plan with the

exception that the forward portion thereof stands slightly at an angle with relation to the rear portion thereof. The frame 89 has side extensions 90 each of which is bent in order that the rear end thereof will stand at an angle to the front portion thereof and the rear end of each extension is provided with a socket 91, designed to receive an arm 92 projecting from a shaft 93. In order to provide for a yielding action of the frame 70 89, the arms 92 are coiled around the shaft 93 as shown in Fig. 10. While this construction is not necessary, it has been found in practice to be quite desirable as it absorbs vibration. The shaft 93 is journaled in the 75 side of the casing in any appropriate way and is provided with an arm 94 which extends into the path of travel of a stud 95, which projects from the dog U, thereby causing the oscillation of the frame as the 80 dog is reciprocated. As the said dog U rises and falls by reason of the operation thereof as heretofore described, the frame 89 with the shaft 93 has a pivot. The relation of parts shown in Fig. 2, indicates that with an 85 upward movement of the dog U, the arm 94 will be moved upwardly, thereby partially rotating the shaft 93 before causing the descent of the frame 89 into the receptacle *a⁴* as shown in Fig. 4. Thus any film that has 90 been delivered to the receptacle 84 will be pressed into the liquid contained therein. The shaft 93 is provided with another arm 96 to which a spring 97 is connected which spring has its opposite end anchored to a 100 stationary portion of the casing. The spring 97 is provided for moving the shaft in a direction opposite to that in which it is moved by the dog U, and said spring is intended to act to return the frame 89 to the 105 position shown in Fig. 2 on the descent of the dog.

While I have termed the means for immersing the film a "frame" it is to be understood that any plunger of a skeleton or solid type designed by its weight or by pressure applied to it to immerse a film shall be regarded as falling within the scope of the term.

I claim—

1. In an apparatus relating to photography, means for containing a supply of film, means for drawing the film therefrom, means in the path of travel of the film for cutting said film, means for spraying the 120 film, and means for carrying the cut film from the cutting means to the means for spraying the said film.

2. A machine relating to photography, containing means for moving film, means in the path of travel of the film for cutting it, means for receiving and carrying the cut film, and a film spraying means to which the film is delivered by the carrying means.

3. In an apparatus relating to photography, a casing, means associated therewith for developing exposed film including a carrier, means for cutting film into lengths proportional to the area of each exposure on the film, means for delivering each severed section to the carrier, a receptacle to which the developed film is delivered, means for spreading the film in its passage from the means for developing the film to the said receptacle, and means for spraying the film on its delivery to the receptacle.

4. In a machine relating to photography, a casing for containing film, means in the casing for developing the film, means for cutting the film into appropriate lengths prior to its development, means for delivering cut sections of film to the developing means and for removing it therefrom, a receptacle to which the film is delivered by the last mentioned means, and means for spraying the film in its travel to the receptacle.

5. In an apparatus relating to photography, a casing, means within the casing for developing exposed film, means for cutting the film into lengths according to the exposures thereon, means for carrying the cut sections of film, a receptacle in position to receive film from the means for carrying it, and means for spraying the film while *en route* to the receptacle.

6. In an apparatus relating to photography, a casing, means therein for conveying film, a receptacle for developing the film in conjunction with which the conveyer acts, a receptacle for fluid into which the film is delivered from the conveyer, means for spreading the film in the receptacle, and means for spraying the film in said receptacle.

7. In apparatus relating to photography, a receptacle for containing developing fluid, means for conveying film there-through, a receptacle positioned to receive film from the conveying means, means for spraying the film in the receptacle, and means for conducting liquid from the receptacle to the spraying means including a motor to operate the conveyer and spraying means.

8. In apparatus relating to photography, means for conveying film, a container for developer in which the conveyer travels, means for guiding the conveyer in the container, means for operating the conveyer, a receptacle in position to receive film from the conveyer, means for spraying the film on its delivery to the receptacle, means of communication between the receptacle and the sprayer, and means for circulating liquid through the said means of communication and sprayer.

9. In apparatus relating to photography, means for developing an exposed film in-

cluding means for carrying said film, a receptacle to which said film is delivered by the carrying means, means for spraying the film while in the receptacle, means for circulating the spraying medium through the means for spraying the film, and means for operating the means for carrying the film.

10. In apparatus relating to photography, a receptacle for containing developer, a receptacle for containing fixing fluid, means for carrying film in the receptacle containing developer and for delivering film to the receptacle containing the fixing fluid, means for operating the means for carrying the film, means for spraying the film in the second mentioned receptacle including a pump, a sprayer pipe, means of communication between the pump and the sprayer pipe, and means of communication between the receptacle and the pump.

11. A photographing and developing apparatus comprising means for containing sensitized film adapted to be exposed to light, means for severing the film into lengths proportional to the area of each exposure on the film, means for carrying the lengths of film, a receptacle into which the films are delivered, and a liquid projecting device discharging into the receptacle to act on the coated surface of the film.

12. A machine relating to photography having means for severing exposed portions of film into appropriate lengths, means for carrying the film, a receptacle to which the film is delivered by the carrier, and a liquid projecting means discharging into the receptacle to communicate motion to the film in the receptacle.

13. An apparatus relating to photography having means for severing exposed portions of film, means for carrying the severed sections of the film, a receptacle adapted to receive the film from the carrying means, and means operating in conjunction with the receptacle to project liquid in said receptacle and adapted to exert force on the film and act on the exposed surface of the film.

14. An apparatus relating to photography having means for severing exposed film, means for carrying the exposed film, a receptacle containing liquid adapted to act on the exposed surface of the film, means for delivering the film to the receptacle, and a liquid projecting means discharging into the receptacle and adapted to exert pressure on the film delivered to the said receptacle.

15. An apparatus relating to photography having means for severing exposed sections of film, a receptacle adapted to contain liquid designed to act on the exposed surface of the film, means for delivering film thereto, and means for drawing the liquid from the receptacle and projecting it against the film.

16. A developing apparatus comprising a

magazine for containing film adapted to be exposed to light, means for drawing the film from the magazine, a carrier for the film, means for cutting film after it is exposed to light, the said cut portion of film being delivered to the carrier, a receptacle to which the film is delivered by the carrier, said receptacle being adapted to contain liquid, a pump in communication with the receptacle receiving liquid from the receptacle, and means for communication between the pump and the receptacle whereby the liquid is forced thereto to act on the film delivered to the receptacle.

15 17. In an apparatus relating to photography, means for spreading a sheet of flexible material to cause it to lie flat, means movable under the sheet approximately above the point of deposit of said sheet to cause it to lie flat, and means for operating the said means.

18. In an apparatus relating to photography, film engaging members, means for delivering film to the said members, means for 25 mounting the members whereby they move substantially horizontally to spread the film, and means for moving the said members.

19. In an apparatus relating to photography, suitably actuated members operable to 30 spread a film, a suitably operated member for delivering film to the spreading members, said delivery member and spreading member being in such relation as to conjointly support the film while the spreading members are in operation.

20. In apparatus relating to photography having a film carrying member, a film spreading member to which the film is delivered by the carrying member, a receptacle 40 containing liquid in which the film is adapted to be delivered by the carrying member and the spreading member, and means for submerging said film in the liquid of the receptacle.

45 21. A developing apparatus relating to photography comprising arms adapted to spread a film, means for pivotally supporting the arms in the developing apparatus, and means for swinging the arms.

50 22. A developing apparatus having swinging arms adapted to spread a film, means for pivotally supporting the arms in the developing apparatus, means for moving the arms, and means for returning the arms to 55 their normal positions.

23. In apparatus relating to photography, oppositely movable arms adapted to act for spreading a film, means for supporting the arms, a member for causing the arms to 60 move, and means for actuating said member.

24. In apparatus relating to photography, a receptacle for receiving film, means movable above the receptacle and toward the edges thereof for spreading said film, and 65 means for supporting the said means where-

by said means are movable over the receptacle.

25. In apparatus relating to photography, a receptacle for receiving film, means movable above the receptacle and toward the 70 edges thereof for spreading said film, supports for the said means, and means for submerging said film.

26. In apparatus relating to photography, a receptacle for receiving film, means movable above the receptacle and toward the 75 edges thereof for spreading the film, supports for the said means, and means for supporting a portion of the film while the spreading means is operated. 80

27. In apparatus relating to photography, a receptacle for receiving film and for containing liquid, means movable above the receptacle and toward the edges thereof for spreading the film, means for supporting a 85 portion of the film while the spreading means is operated, and means for submerging the film in the liquid in the receptacle.

28. In an apparatus relating to photography, a receptacle for receiving liquid and 90 film, means movable above the receptacle and toward the edges thereof for spreading the film in the liquid, means for supporting a portion of the film while the spreading means is operating, and means for disengaging 95 the film from the supporting means.

29. In apparatus relating to photography, a receptacle for receiving liquid and film, means movable above the receptacle and toward the edges thereof for spreading the 100 film in the liquid, means for supporting a portion of the film while the spreading means are operating, and means for disengaging the film from the supporting means and simultaneously submerging said film in 105 the liquid in the receptacle.

30. In an apparatus relating to photography, means for containing film, means for drawing film therefrom, means for cutting the film, a conveyer for the cut film, a receptacle into which the conveying means delivers film, projecting means operated to project liquid to act on the film delivered to the receptacle, and mechanically operated means for spreading the cut film in the 110 receptacle. 115

31. An apparatus relating to photography comprising means for containing film, means for conveying film therefrom, a receptacle into which the conveying means delivers film, means for cutting film delivered to the conveying means, liquid projecting means operating to project liquid to act on the film delivered to the receptacle, film engaging members to which the film is delivered by the conveyer and operable to spread the film while a portion of the said film is supported by the conveyer. 125

32. An apparatus relating to photography comprising means for conveying film, a 130

receptacle in position to receive film from the conveying means, liquid projecting means in the receptacle for delivering liquid to the film in the receptacle, film engaging members, means for mounting the film engaging members whereby they may swing substantially horizontally with relation to the receptacle to engage and spread the film therein, and means for displacing the film 10 from the carrier.

33. An apparatus relating to photography having means for conveying film, a receptacle for receiving film from the conveying means, liquid projecting means in the receptacle, film engaging members, means for mounting the film engaging members to operate over the receptacle, means for actuating the film engaging members laterally of the film to spread the same while a portion 20 thereof is held by the conveying means, and means for displacing the film from the conveying means and submerging said film in the liquid contained in the receptacle.

34. An apparatus relating to photography having means for conveying film, a receptacle into which the conveying means delivers film, a liquid projecting means located to project liquid on the film delivered to the receptacle, film engaging members, means 30 for mounting the film engaging members, whereby they operate over the receptacle to spread a portion of the film therein while the other portion of said film is being supported by the conveyer means, and means 35 for moving said film engaging members.

35. An apparatus relating to photography having means for conveying film, a receptacle into which the conveying means delivers film, swinging arms, means for mounting the swinging arms whereby they operate across the receptacle to spread film while a portion of said film is supported by the conveying means, means for moving the arms in one direction, and means for returning 45 said arms.

36. An apparatus relating to photography having means for conveying film, a re-

ceptacle into which the conveying means delivers film, film engaging members, means for mounting the film engaging members to 50 operate over the receptacle and in such relation to the means for conveying film that said film engaging members spread a portion of the film while a portion thereof is being supported by the conveying means, 55 and means for moving the film engaging members oppositely.

37. An apparatus relating to photography having means for conveying film, a receptacle in such relation to the conveying 60 means as to receive film therefrom, liquid projecting means within the receptacle, film engaging members, means for mounting the film engaging members whereby they move over the receptacle and in such relation to 65 the conveying means as to coact therewith in supporting and spreading film delivered to the receptacle, and means for actuating the film engaging members.

38. An apparatus relating to photography having means for conveying film, a receptacle into which the conveying means delivers film, film engaging members, means for mounting the film engaging members between the receptacle and the means for conveying the film, means for moving the film engaging members in one direction into and out of engagement with the film, and means for moving the film engaging members in the opposite direction. 70

39. In an apparatus relating to photography, an arm, means for moving the arm in engagement with the surface of a film to spread the same, means for delivering film to said arm, and a receptacle in such relation to the arm as to receive the spread film. 80

In testimony whereof, I have hereunto affixed my signature in the presence of two witnesses.

GEORGE C. BEIDLER.
